UNITED STATES PATENT OFFICE.

WILLIAM LAWRENCE, OF NEW YORK, N. Y., ASSIGNOR TO THE LAWRENCE ELECTRIC COMPANY, OF SAME PLACE.

ELECTRIC ENGINE.

SPECIFICATION forming part of Letters Patent No. 503,487, dated August 15, 1893.

Application filed August 17, 1892. Serial No. 443,323. (No model.)

To all whom it may concern:

Be it known that I, WILLIAM LAWRENCE, a citizen of the United States, residing at the city of New York, in the county of New York and State of New York, have invented a new and useful Electric Engine, of which the following is a specification.

My invention relates to improvements in electric street car-engines, and has for its objects, among others, first, to provide a machine which is capable of propulsion without the use of gears, &c.; second, to produce a greater amount of power with less electric current; and third, to provide means whereby the mechanism may be started, stopped, and reversed by a single lever, a description of which improvements will appear hereunder.

In my invention the power is applied directly to the axles of the machine from the magnet plates or armatures through suitable connecting rods.

I will now proceed to describe my invention, reference being had to the accompanying drawings forming a part of this specification.

Similar letters of reference indicate corresponding parts in the different figures.

Figure 1 is a side elevation partly in section of a car showing the magnets, armatures, and connecting rods in their operative positions. Fig. 2 is an inverted plan view of my improved apparatus showing clearly all the mechanism employed. Fig. 3 is a perspective view of the shafts, connecting rods, and brushes, also the rod for controlling the brushes, which in turn control the current of electricity, and start, stop, and reverse the car. Fig. 4 is a perspective view of a set of magnets and armature employed in my machine. Fig. 5 is a perspective view showing a modified form of apparatus, wherein the magnets are placed horizontally one above the other, the armature having a lateral movement, and a direct connection being formed between said armature and the crank shaft by means of a connecting rod.

Referring to the drawings, it will be seen that four sets of electro magnets A are employed, each of which sets are provided with a vertically moving armature B. Connected with or depending from these armatures B are arms or bars C to the outer ends of which

arms or bars are pivotally secured the driving rods D, which connect at their opposite ends with connecting rods D'; said rods D' in turn being suitably journaled on the cranks E of the axles E'.

55

To the under side of the bed F which carries the mechanism are attached four sets of electric contact brushes G, said brushes being fork-shaped, and preferably formed from a continuous strip or piece. Said brushes G are connected with an operating rod or bar H by arms b (best shown in Fig. 3), and are operated by said rod or bar H and a lever I from either end of the car. The current is taken from the track by the wheels of the car and passes thence through the axles E', and contacts a, situate thereon, to the forked brushes G, whence it is conveyed alternately by one member of the brushes through the wires L' and magnets A.

70

A current distributor J consisting of a plate of any suitable conducting material, and of any desired shape and size, is secured to the bed F of the machine by screws, bolts, or otherwise, and its function is to receive a current 75 of electricity, and distribute the current through the wires L to the magnets A.

The operation of my improved mechanism is as follows:—When the lever I is in the position shown in Fig. 1, the car will move in the direction shown by the arrow, the current passing in from the track or underground wire. In the former instance the current is taken from the track by the wheel and passes through the axle and is then taken from the 85 axle and conveyed to one pole of the magnets by the brushes G and wires L'; while in the other case the current is taken from an underground service and conveyed to the current distributor and thence through the wires 90 L to the opposite pole of the magnets and to the wheels and tracks forming a complete circuit, and attracting the armatures, alternately causing them to communicate motion to the axles through the driving rods previously 95 mentioned. To reverse the mechanism the lever I is pushed in the opposite direction, which movement reverses the positions of the brushes, causing the cranks to operate reversely, and thus move the bar in the oppo- 100

site direction. To stop the mechanism the lever I is brought to a vertical position, thereby breaking the circuit.

In Fig. 5 I have shown a modified form of the manner in which the connection is made between the armature and the driving shaft.

In this modification I place the magnets A in a horizontal position, one above the other, and I adjust the armature B in suitable bearings 10 f in a vertical position relatively to said magnets, whereby said armature will have a lateral movement. A direct connection is made between said armature and one end of the driving shaft E' by means of drive rod D, which in this modification is seen to be pivotally connected directly with the armature. The said drive rod is suitably journaled at its other end to the crank of the driving shaft E'.

Although I have described and illustrated my invention as applicable to the propulsion of a car in connection with an underground current of electricity, I am well aware that the mechanism herein shown may be employed 25 for stationary engines as well as for the propulsion of boats in connection with any known electrical storage system. Consequently I do not wish to limit myself to the use of my invention for propelling cars.

Having now described my invention, what I claim, and desire to secure by Letters Patent, is—

1. In an electric propelling apparatus one or more pairs of electro magnets secured in 35 and to a suitable bed, an armature for said magnets, an arm connected to and operated by said armature, a rod pivotally secured to the lower end of said arm and connecting with a rod which is journaled to the cranks 40 formed directly on the axis, all substantially as and for the purposes shown and described.

2. In an electric propelling apparatus an electro magnet secured in and to a suitable bed, an armature for said magnet, an arm 45 connected to and operated by said armature, a rod pivotally secured to said arm and connecting with cranks for turning axles, contact points suitably secured to the axles for opening and closing circuits, electric contact

50 brushes secured to the bed and a rod or bar for operating said brushes, and levers connected with said rod or bar for controlling

the movement of same, and thereby the current of electricity, substantially as shown and described.

55

3. In an electric propelling apparatus one or more pairs of electro magnets secured in and to a suitable bed, an armature for said magnets, an arm connected to and operated by said armature and magnets, a rod pivotally secured to the lower end of said arm and connecting with a rod which is journaled to the cranks formed directly on the axle, contact points suitably secured to the axle for opening and closing the circuits, electric contact 65 brushes secured to the bed and operated by a rod or bar and levers and controlling the movement of said brushes, substantially as shown and described.

4. The improvements in electric controlling 70 apparatus consisting of a forked brush formed from a continuous strip or piece, an arm connected with said brush, for moving the latter, a rod or bar connected with said arm and adapted to be operated from either end, and 75 a lever for operating said rod or bar to control the movement of the apparatus and also the current of electricity substantially as shown and described.

5. The improvements in electric controlling 80 apparatus consisting of a forked brush formed from a continuous strip or piece pivoted to the bed of the machine, an arm secured to said pivot for moving the brushes vertically, which arm is connected to a rod or bar and 85 adapted to be operated from either end of the apparatus by a lever, and thereby control the movement of the apparatus, substantially as shown and described.

6. Four or more sets of magnets, armatures 90 therefor cranks and connections between said armatures and said cranks, said cranks being set at angles to each other, combined with contacts and brushes therefor, said brushes being arranged to be moved to bring one 95 member at a time into engagement with said contacts, whereby the cranks will be moved in opposite directions according to the positions of said brushes, substantially as described.

WILLIAM LAWRENCE.
